STABILIZER FOR A FLOATING DOCK

William L. Koch, San Francisco, Calif., assignor to H. Koch & Sons, Corte Madera, Calif., a corporation of California

Filed Nov. 14, 1960, Ser. No. 68,905

2 Claims. (Cl. 61—48)

This invention refers to a stabilizer for a floating dock and the like.

A particular object of this invention is to provide a stabilizer for a floating dock which can maintain an elongated floating structure in a location or position yet permit the structure to rise and lower with the tides and waves.

Particularly it is an object of this invention to provide a submerged stabilizer for a floating dock of the type constructed of spaced floats and spacer plates connected into a continuous floating deck, whereby this submerged stabilizer can hold the float in a location yet permit it to raise or lower with the water level.

I am aware that some changes may be made in the general arrangements and combinations of the several devices and parts, as well as in the details of the construction thereof without departing from the scope of the present invention as set forth in the following specification, and as defined in the following claims; hence I do not limit my invention to the exact arrangements and combinations of the said device and parts as described in the said specification, nor do I confine myself to the exact details of the construction of the said parts as illustrated in the accompanying drawings.

With the foregoing and other objects in view, which will be made manifest in the following detailed description, reference is had to the accompanying drawings for the illustrative embodiment of the invention, wherein:

FIG. 1 is a fragmental cross-sectional view of the stabilizers anchored in the bottom of the body of water holding the floating structure in position.

FIG. 2 is an enlarged cross-sectional view of one of the stabilizer structures taken on the lines 2—2 of FIG. 1. 40

FIG. 3 is a top plan view of the floating structure, the deck being partly broken away, showing the relative location of the stabilizers.

FIG. 4 is a fragmental bottom view illustrating the mounting of the top of the stabilizer on the floating structure. 45

FIG. 5 is a fragmental sectional view of the mounting of the stabilizer, the section being taken substantially on lines 5—5 of FIG. 4.

This floating structure, as herein illustrated, is made of a plurality of fiberglass floats 1 which are made of hollow waterproof fiberglass plastic shells completely enclosed so that the top plates 2 of the floats 1 form part of the walk or deck of the structure. The floats 1 are spaced by suitable spacer plates 3 between them and are secured together and held by a suitable frame of longitudinal stringers 4 and cross-stringers 5, illustrated diagrammatically in FIGS. 1 and 3, to hold the structure together.

This floating structure may be made in any suitable size, shape, dimension or such strips in any overall arrangement to form a suitable deck.

The anchoring of such structures in such a manner to hold them more or less accurately in location is of importance because they may be used as part of other structures where the constant spacing is of importance.

For this purpose the stabilizer means of the present illustration include a ballast base 6 which is suitably anchored or secured in the bottom 7 of the water body 8 on the surface 9 of which the floating structure floats. 70 Inside of this anchored ballast 6 is telescopingly guided a hollow vertical tubular leg 11. The top of the leg 11 is

2

provided with a head flange 12 which is then secured by suitable bolts 13 to a head plate 14. This head plate 14 is suitably secured in turn to cross bars 16 which latter in turn have their ends suitably secured, for instance by screws, to the frame bars 4 and 5 of the floating structure.

In the present illustration the ballast 6 is a pipe 17, the lower end of which is closed preferably by a frusto-conical tip 18 so that it may be driven considerably below the mud level of the bottom 7. The upper portion of this pipe 17 projects at a suitable distance above the bottom 7 so as to prevent interference by the mud with the relative movement of the parts. On this upper end of the pipe 17 is suitably fixed a rubber disc 19 the inner diameter of which fits tightly around the outer circumference of the telescopic tube 11 so as to wipe the latter during its reciprocation and thereby to reduce the possibility of its sticking in the pipe 17.

The top of the tube 11 is open and the head plate 14 has a central hole 21 uncovered so as to provide a vent through which air can escape as the tube 11 telescopes into and out of the pipe 17. This hole 21 is spaced below the deck plate 3 so as to provide sufficient space for venting.

The stabilizers are spaced apart at suitable distances and it is not necessary to have the stabilizers close together because they do not contribute to the support of the structure but only for stabilizing the same in a location and to limit the movement or displacement of said floating structure only to vertical directions, and prevent lateral displacement or floating away in either direction.

I claim:

1. In combination with a floating deck on a body of water including spaced floats and deck plate elements connecting said spaced floats to form a continuous deck, a stabilizer structure comprising
  - (a) spaced anchor elements fixedly secured to the bottom of said body of water
  - (b) a tubular element telescopingly supported on each anchor element
  - (c) means on each tubular element securing the top of each tubular element to said floating deck between a pair of adjacent floats
  - (d) said tubular element being open at its top and bottom for freely venting said tubular element during reciprocation
  - (e) said anchor element consisting of a tube driven in the bottom of said body of water
  - (f) said tubular element telescoping inside said tube
  - (g) said securing means including a securing flange on the top of the tubular element
  - (h) and a headplate secured to the underside of a deck plate and having a venthole registering with the top of said tubular element
  - (i) said flange being secured to said headplate.
2. The invention defined in claim 1, and
- (j) a wiper flange secured to the top of each tube and surrounding the tubular element therein with sufficient tightness to wipe the same during its reciprocation in opposite directions.
